UNITED STATES PATENT OFFICE.

HENRY J. PLANT, OF ROCHESTER, NEW YORK, ASSIGNOR TO DEFIANCE CHECK WRITER CORPORATION, OF ROCHESTER, NEW YORK, A CORPORATION OF NEW YORK.

CHECK-WRITING MACHINE.

1,254,270.

Specification of Letters Patent. Patented Jan. 22, 1918.

Application filed April 14, 1916, Serial No. 91,014. Renewed July 10, 1917. Serial No. 173,768.

To all whom it may concern:

Be it known that I, HENRY J. PLANT, a citizen of the United States, and resident of Rochester, in the county of Monroe and State of New York, have invented certain new and useful Improvements in Check-Writing Machines, of which the following is a specification.

The present invention relates to printing machines and, more particularly, to the type in which words or characters of different lengths are printed and the work is fed distances corresponding to the word printed, an object of this invention being to provide a construction in which the printing couple make a complete imprint of the printed matter on the coöperation of the couple and move during such coöperation in the direction of the printing line for effecting the feeding of the work so that expensive and complicated feeding devices are eliminated, and at the same time the work is engaged by the couple throughout the entire length of the printed line during the feeding action, such engagement overcoming any tendency for the shifting of the work out of alignment during such feeding. Another object of the invention is to provide, in a printing mechanism in which a rotary printing member is shiftable in the direction of its turning axis, an inking mechanism which is thrown out of coöperation with the printing mechanism during such shifting action.

To these and other ends, the invention consists of certain parts and combinations of parts all of which will be hereinafter described, the novel features being pointed out in the appended claims.

In the drawings:—

Figure 1 is a vertical section through one embodiment of the invention on the line *a—a*; Fig. 2;

Fig. 2 is a vertical section on the line *b—b*, Fig. 1;

Fig. 3 is a bottom view of the machine illustrated in Fig. 1;

Fig. 4 is a section on the line *c—c*, Fig. 1; Fig. 5 is a development of the type cylinder;

Fig. 6 is a detail view of the indicator;

Fig. 7 is a perspective view of the platen;

Fig. 8 is a perspective view of the device which cooperates with the type cylinder to center the latter over the printing point and

to shift the printing member in the direction 55 of the printing line; and

Figs. 9 and 10 are detail views of the inking mechanism.

According to the present invention, a printing couple is employed in which the 60 printing die is engaged at once throughout its entire length upon a relative movement of the couple, and during such engagement the printing couple is moved in the direction of the printing line to feed the work a distance equal to the length of the printed word plus an additional amount to provide a spacing between this word and the word to follow, or the word previously printed. In the 65 illustrated embodiment of the invention, the relative movement between the printing member and the platen or other member of the couple is effected by moving the platen toward the printing member, but it is apparent that the invention is not limited to 70 this means of effecting this relative movement, but that any other construction can be employed where the same result is produced.

Referring particularly to the illustrated embodiment of the invention, 1 indicates the 75 base portion of the main frame, which has a work-supporting plate 2 secured to the upper surface thereof and an upper frame portion 3 also secured to the upper surface thereof in the rear of the work-supporting 80 plate and projecting forwardly over said plate.

In this forwardly-projecting portion, a printing member 4 is mounted, said member being preferably in the form of a type wheel 85 having lines of type 5 projecting therefrom in parallel relation, said lines being parallel to each other and also to the axis of turning of the printing wheel. In this instance these lines are adapted to print words "one" to 90 "nineteen," "twenty," "thirty," "forty," etc., "hundred," "thousand," "dollars," "cents," and "only," so that it is possible to fill in a 95 check or other negotiable instrument any amount in words within the limit of the machine. Preferably the faces of the type are provided with depressions or grooves for co-operation with the platen to be hereinafter described. The printing member is movable 100 in the direction of its axis, and, to this end, 105 is supported for longitudinal movement on a non-circular shaft 6 which is journaled at 7 and 8 in the side walls of the overhanging

portion 3. A spiral spring 9 abuts at one end this printing member 4 and at the other end abuts a side wall of the casing 3 to hold the printing member against the opposite side wall of the casing.

An extension 10 on the non-circular shaft 6 projects to the exterior of the casing where it is provided with a thumb wheel 11 by which the shaft and printing member may be turned. On this thumb wheel a flange 12 is formed, the exterior of which is provided with characters corresponding to the words on the printing wheel, a pointer or index 13 projecting from the casing 3 over the periphery of the flange to cooperate with the characters.

For centering the printing wheel, a centering device is employed preferably in the form of a ball 14 operated in a pocket 15 20 formed in a lug 16 extending from the casing 3 within the flange 12, a spring 17 in the pocket acting on the ball to press the latter into cooperation with the inner periphery of the flange 12, said periphery being notched or grooved at 18 to receive the ball, the grooves corresponding in number to the number of lines of type in the printing wheel.

The other printing element is preferably 30 in the form of a platen 19 having a surface 20 provided with projections or otherwise roughened to register with the grooves or depressions on the faces of the type so that the paper will be bruised, torn, or broken 35 during the printing action, permitting the ink to penetrate the fiber of the paper and thus rendering more difficult the surreptitious changing of the printed matter. This platen is mounted for movement toward and 40 from the printing member, and is also adapted to move in the direction of the printed line. In the illustrated embodiment, a guide portion 21 is provided on the platen for movement on a guide 22. This 45 guide 22 is movable toward and from the printing member and, to this end, is preferably mounted on a lever 23, pivoted at 24 between its ends to the base 1, which is turned on its pivot by a mechanism herein- 50 after described to carry the platen 20 to the printing wheel preferably after the latter has been locked in its printing position. A spring 25 acts on a spring arm 26 on the lever 23 to swing the latter to carry the 55 platen 20 away from the printing wheel, while a spring 27 secured at one end to the platen guide 21, and its other end to the base 1 at 28, normally holds the platen at one end of the guide 22.

60 A mechanism for moving the platen toward the printing wheel embodies preferably a lever or operating arm or member 29 secured to a shaft 30, which is journaled in the casing 3 in a horizontal position trans- 65 versely of the turning axis of the printing

member, and carries a gear segment 31 which, in turn, meshes with a pinion segment 32, turning on a stub shaft 33 within the casing. The pinion-segment has a hub which supports a cam wheel 34 which, in this instance, has three surfaces 35 for engagement with a roller 36 arranged on the upper end of an arm 37, extending upwardly from the rear end of the lever 23, through an opening 38 in the main frame at the connection of the upper part 3 with the case part 1. A ratchet 39 is formed on the hub of the pinion segment and has three teeth engaged by a pawl 40 which is pivoted at 41 to the cam wheel. A spring 42 acts on the pawl to hold it to the ratchet. The pawl causes the cam wheel 34 to turn in one direction with the pinion segment, and permits the pinion segment to turn in the other direction without turning the cam. A spring 43 is secured at one end to a segmental gear 31 and the other end to a fixed part so as to return the segmental gear, operating lever 29, and the ratchet to normal position.

With the end in view of preventing the return of the operating member 29 until the feeding of the work has been effected after the printing action, a toothed portion 44 is provided on the segment 31 concentric with the turning axis of the latter, and, with this toothed portion, a pivoted pawl 45 is adapted to cooperate, said pawl being acted upon by a spring 46 which permits the pawl to swing to either side from its normal position. When the segment 31 is moved in the direction to effect the printing and the feeding of the work, the pawl rides over the teeth 44 and prevents the return of the segment until the end of the toothed portion 44 is reached, when the pawl is freed and the spring returned to its normal position, so that, on the return movement of the segment 31, the pawl will ride over the teeth 44.

The feeding of the work is effected by shifting the printing couple in the direction of the printing line after the printing has been completed, the distance of this shifting being equal to the length of the printed word, plus an amount equal to the space between such word and the next word to be printed or the previously printed word. This feeding and spacing is effected in this instance by providing a plurality of stop shoulders 47 preferably on the printing member, said shoulders being located at different distances from a common plane, their locations corresponding to the lengths of the different lines of type on the printing members. In this instance, these shoulders are provided at the ends of grooves 48 formed in the printing member between the type lines 5, and in any one of these grooves operates a device 49 in the form of a projection on a slide 50, which is mounted on a guide 51 parallel with the axis of turn- 130

ing of the printing member. An arm 52 on the operating lever 29 has a slotted end 53 engaging a pin 54 on the slide 50 to move such slide when the operating member 5 is moved. This projection 49 normally lies out of the path of the printing member, but, upon the first part of the movement of the operating member 29, the projection or device 49 enters the groove 48 and locks the printing member against turning. After the platen engages the printing wheel to effect the printing, the projection or device 49 enters into engagement with the shoulder 47 at the end of the slot, and shifts the printing wheel in the direction of its axis, causing the platen to move therewith, due to the registering projections and grooves on said parts.

Inking of the printing wheel may be effected in any suitable manner. In this instance, an ink roller 55 is provided, journaled on a shaft 56 which is mounted upon a swinging frame 57, that is pivoted at 58 to a plate 59 which, in turn, is removably held 25 to the casing part 3 by a latch 60 and a rib 61 which it engages in a grooved portion 62 on said plate 59. A spring 63 acts on the swing or movable frame 57 to hold the latter toward the printing wheel. It is desirable to move the inking roller or member 30 out of co-operation with the printing wheel when the latter moves in the direction of its axis, and, to this end, the pivoted carrier or frame 57 carries a shifting device 64 in the 35 form of a blade lying to one side of the inking roller and having a curved or beveled end 65 which, when the printing member or wheel is moved in the direction of its axis, is engaged by the portions of the printing 40 wheel between the printing lines, causing the inking roller 55 to be shifted away from the printing wheel so that the latter may continue its movement without rubbing over the face of the printing wheel.

To print a check or other negotiable instrument, the latter is placed upon the work support or table 2 against a gage 66 which is arranged at the rear of the work support. The handle or operating member 29 is then 45 depressed, causing the device 49 to enter a groove 48, thus locking the printing wheel against turning. Further movement of the lever causes a cam portion 35 to act upon the platen lever 23, and move and hold the platen against the line of type over the slot 67 in the plate 68 which closes the lower portion of the overhanging casing 3, the platen passing upwardly through a slot 69 in the table 2 and through the slot 67. After 50 such engagement, the projection 49 engages the adjacent shoulder 47 and causes the type wheel 4 to shift in the direction of its axis, the platen being carried therewith due to the interengaging projections and grooves on the platen and type wheel. When the end

of a line is reached, the roller 36 passes off the cam portion 35 into a recess 35, thus permitting the spring 25 to act upon the lever 23 and to lower the platen 20, which then springs back to normal position on the 70 guide 22 under the action of the spring 27. Upon the release of the hand lever 29, the spring 9 returns the printing wheel to normal position so that the hand wheel 11 may again be turned to present another word 75 die to printing point. The hand lever can not be returned to its initial position until it has been moved completely to the end of the stroke, this being due to the fact that it is locked against return by the dog or pawl 45. 80 According to this invention, the printing is effected by a relative movement of the printing couple one toward the other. This grips the work between them after which the work is fed by the printing couple due to 85 the movement of said couple in the direction of the printing line. At the end of the feeding movement, the couple automatically separate, so that the work will be maintained in its advanced position and the couple will be 90 returned to their initial positions. The inking devices are thrown out of connection with the printing wheel so that movement of the latter will not be retarded by such inking devices. A machine embodying the foregoing method of operation dispenses with 95 complicated feeding devices and, at the same time, makes it possible to obtain the printing of an entire word by the relative movement of the platen and the printing wheel, the 100 printing action of the couple being entirely distinct from the feeding action.

It will be understood that certain features of this invention are not limited to a construction in which the platen is moved 105 bodily with the printing member in the direction of the printing line, but may, within the scope of the appended claims, be used in any other construction where any of the functions of such features can be performed. 110

What I claim as my invention and desire to secure by Letters Patent is:

1. A printing machine comprising a printing member, having a plurality of lines of type thereon, and a common platen for said lines adapted to engage any one of such lines throughout the length of the line at one time, the platen and printing member having a relative movement to present any line to the platen, and also a relative movement to bring the platen and printing member together for printing; and being movable together in the direction of the printing line to feed the work.

2. A printing machine comprising a printing member, having a plurality of lines of type thereon, and a common platen for said lines adapted to engage any one of such lines throughout the length of the line at one time, the platen and printing member hav- 130

- ing a relative movement to present any line to the platen, and also a relative movement to bring the platen and printing member together for printing; and being movable together in the direction of the printing line to feed the work, and means for automatically returning the platen to its initial position at the completion of the feeding movement.
10. 3. A printing machine embodying a plurality of lines of type of different lengths, a common platen for coöperating with any of said lines of type throughout the length of the line, and mechanism for effecting a relative movement between any one of the lines of type and the platen for printing, said mechanism also being adapted to move the platen and the line of type in the direction of the printing line a distance corresponding to the length of said line of type.
4. A printing machine comprising a printing member mounted to turn about an axis and provided with a plurality of parallel lines of type thereon extending in the direction of the axis, a platen with which any one of said lines is adapted to coöperate throughout its length, said printing member and platen being both movable in the direction of the axis of the printing member and having a relative movement to bring them into and out of coöperation.
5. A printing machine comprising a printing member mounted to turn about an axis and provided with a plurality of parallel lines of type of different lengths extending in the direction of the axis, a platen with which any one of said lines is adapted to coöperate throughout its length at one time, said printing member and platen being both movable in the direction of the axis of the printing member and having a relative movement to bring them into and out of coöperation, a plurality of stop shoulders having positions corresponding to the lengths of the lines of type on the printing member, said stop shoulders being moved simultaneously with the printing member, and mechanism for bringing the printing member and the platen into coöperation, said mechanism having a device for coöoperating with the stop shoulders to move the printing member and the platen in the direction of the axis of the printing member, after the platen and the printing member have been brought into coöperation.
6. A printing machine comprising a rotary printing member having a plurality of parallel lines of type extending in the direction of the axis of the printing member, the face of the type being provided with grooves and the printing member being movable in the direction of its axis, a platen for coöperation with any one of the lines of type on the printing member and having projections to enter the grooves of said type,
- said platen being movable in the direction of the axis of the printing member, and mechanism for effecting a relative movement between the platen and the printing member to bring them into coöperation to effect the printing, then to move them together in the direction of the axis of the printing member to feed the work in the direction of the printing line, and then to separate the printing member and the platen prior to their return to their initial position.
7. A printing machine comprising a rotary printing member having a plurality of parallel lines of type of different lengths extending in the direction of the axis of the printing member, said printing member being movable in the direction of its turning axis, a platen for coöperating with any one of the lines of type on the printing member and also movable in the direction of the axis of the printing member, and mechanism for effecting a relative movement between the platen and the printing member to bring them into coöperation to effect the printing, then to move them in the direction of the axis of the printing member to effect the feeding of the work, and then to automatically separate the platen and the printing member before these parts have returned to their normal positions.
8. A printing machine comprising a rotary printing member having a plurality of parallel lines of type of different lengths extending in the direction of the axis of the printing member, said printing member being movable in the direction of its turning axis, a platen for coöperation with any one of the lines of type on the printing member and also movable in the direction of the axis of the printing member, mechanism for effecting a relative movement between the platen and the printing member to bring them into coöperation to effect the printing, then to move them in the direction of the axis of the printing member to effect the feeding of the work, and then to automatically separate the platen and the printing member before these parts have returned to their normal positions, and means adjustable with the printing member for determining a feeding movement of the platen and the printing member corresponding with the length of the type line printed.
9. A printing machine comprising a rotary printing member having a plurality of parallel lines of type of different lengths extending in the direction of the axis of the printing member, said printing member being movable in the direction of its turning axis, a platen for coöperation with any one of the lines of type on the printing member and also movable in the direction of the axis of the printing member, mechanism for effecting a relative movement between the platen and the printing member to bring

- them into cooperation to effect the printing, then to move them in the direction of the axis of the printing member to effect the feeding of the work, and then to automatically separate the platen and the printing member before these parts have returned to their normal positions, and means adjustable with the printing member for determining a feeding movement of the platen
- 10 and the printing member corresponding with the length of the type line printed, said means comprising a plurality of shoulders arranged at different distances from a common plate and adjustable with
- 15 the printing wheel into operative connection with the mechanism which shifts the printing wheel axially.
10. A printing machine comprising a rotary printing wheel having a plurality of parallel lines of type thereon of different length extending in the direction of its axis, said printing wheel being movable in the direction of its axis for feeding the work, and mechanism for shifting said printing
- 20 wheel axially different distances corresponding to the different lengths of the lines of type.
11. A printing machine comprising a printing member having a plurality of lines of type thereon of different lengths, said member being adjustable transversely of the printing line to bring the different lines of type to printing position, and mechanism for moving said member different distances in
- 25 the direction of the printing line to correspond with the length of the word printed.
12. A printing machine comprising a rotary printing wheel having a plurality of lines of type thereon of different lengths, extending in the direction of the axis of the wheel, said wheel being movable in the direction of its turning axis, a plurality of shoulders carried by the wheel and arranged at different distances from one side
- 30 of the wheel, and mechanism for moving the wheel axially, coöperating with said shoulders.
13. A printing machine comprising a rotary printing wheel having a plurality of lines of type thereon of different lengths, extending in the direction of the axis of the wheel, the wheel being movable in the direction of its axis and being provided between its printing lines with grooves forming
- 35 shoulders at their inner ends situated at different distances from one face of the wheel, and operating mechanism of constant throw coöperating with said shoulders to move the wheel different distances in
- 40 the direction of its axis to correspond with the different lengths of the lines of type.
14. A printing machine comprising a printing member having a plurality of lines of type thereon of different lengths, said
- 45 member being adjustable transversely of the printing line to bring the different lines of type to printing position, a platen mechanism for effecting a relative movement between the platen and the printing mechanism, and a plurality of shoulders arranged in different positions to correspond with the different lengths of the lines of type and movable with the printing member into operative connection with the mechanism which effects the relative movement between the platen and the printing member in order that said mechanism will shift the printing member in the direction of the printing line a distance corresponding to the length of the line of type at printing position.
15. A printing machine comprising a printing member having a plurality of lines of type thereon of different lengths, said member being adjustable transversely of the printing line to bring the different lines of type to printing position, a platen, mechanism for effecting a relative movement between the platen and the printing mechanism, and a plurality of shoulders arranged in different positions to correspond with the different lengths of the lines of type and movable with the printing member into operative connection with the mechanism which effects the relative movement between the platen and the printing member in order that said mechanism will shift the printing member in the direction of the printing line a distance corresponding to the length of the line of type at printing position, the mechanism which effects the relative movement between the platen and the printing member having provision for separating these two parts after the printing member has been moved to the end of its feeding movement.
16. A printing machine comprising a printing member having a plurality of lines of type thereon said member being adjustable transversely of the printing line to bring the different lines of type to printing position, and being movable in the direction of the printing line, a platen, a guide for the platen extending in the direction of the printing line, and an operating member having connection with the guide to move the latter and the platen toward the printing member and having connection with the printing member to move the latter in the direction of the printing line.
17. A printing machine comprising a printing member having a plurality of lines of type thereon of different lengths, said member being adjustable transversely of the printing line to bring the different lines of type to printing position and being movable in the direction of the printing line, a platen, a guide for the platen extending in the direction of the printing line, a plurality of shoulders arranged in different positions to

correspond with the different lengths of the lines of type and movable with the printing member, and mechanism for moving the platen and its guide toward the printing member, said mechanism having a device for coöperating with the shoulders in order to shift the printing member in the direction of the printing line after the platen has moved into coöperation with the printing member.

18. A printing machine comprising a printing member having a plurality of lines of type thereon of different lengths, said member being adjustable transversely of the printing line to bring the different lines of type to printing position and being movable in the direction of the printing line, a platen, a guide for the platen extending in the direction of the printing line, a plurality of shoulders arranged in different positions to correspond with the different lengths of the lines of type and movable with the printing member, mechanism for moving the platen and its guide toward the printing member, said mechanism having a device for coöperating with the shoulders in order to shift the printing member in the direction of the printing line after the platen has moved into coöperation with the printing member, and said mechanism having provision for moving the platen away from the printing member after the feeding movement of the latter has been completed, and a spring acting on the platen to return it to its normal position on the guide.

19. A printing machine comprising a printing member having a plurality of lines of type thereon, said member being adjustable transversely of the printing line to bring the different lines of type to printing position, and being movable in the direction of the printing line, a platen, a guide for the platen extending in the direction of the printing line, mechanism for effecting a relative movement between the platen guide and the printing member to bring the platen and printing member into coöperation, said mechanism having connection with the printing member to shift the latter and the platen in the direction of the printing line after coöperation between the platen and the printing member, and said mechanism having provision for automatically effecting the separation of the platen and the printing member after the feeding movement of the printing member has been completed, and a spring acting on the platen to return it to its normal position on the guide after the separation of the platen and the printing member.

20. A printing machine comprising a printing member having a plurality of lines of type thereon, said member being adjustable transversely of the printing line to bring any line of type to printing position

and also being movable in the direction of the printing line, a platen movable toward and from the printing member, an operating member having connection with the printing member to move the latter in the direction of the printing line, a rock shaft on which said operating member is mounted, a rotary cam member, a ratchet driving connection between said rock shaft and the rotary cam member for turning the rotary cam member in one direction only, and connections between said cam member and the platen for moving the latter toward the printing wheel before the printing wheel moves in the direction of the printing line and for automatically effecting the movement of the platen away from the printing member when the end of the movement of the printing member is reached.

21. A printing mechanism comprising a printing member having a plurality of lines of type thereon, said member being adjustable transversely of the printing line to bring any line of type to printing position and also being movable in the direction of the printing line, a platen movable toward and from the printing member, an operating member having connection with the printing member to move the latter in the direction of the printing line, a rock shaft on which said operating member is mounted, a segmental gear on the shaft, the segmental pinion meshing with the gear, a ratchet wheel turned by said pinion, a rotary cam member having a pawl for coöperation with the ratchet, and a lever having one end connected to the platen and the other end coöperating with the rotary cam member.

22. In a printing machine, a printing wheel, a casing inclosing said wheel, a thumb wheel arranged on the exterior of the casing provided with an annular flanged portion disposed toward the casing, the exterior of said flange having matter corresponding to the matter on the printing wheel and the interior face of the flange having centering grooves, and a centering device mounted on the exterior of the casing for operating in said centering grooves, the centering device being surrounded by the flange.

23. In a printing machine, a rotary printing member having a plurality of lines of type thereon, said member being movable in the direction of its turning axis, an inking roller for coöperation with the printing wheel, and means for automatically throwing the inking roller out of coöperation with the printing wheel when the latter moves in the direction of its axis.

24. In a printing machine, a printing member having a plurality of lines of type thereon, said member being adjustable transversely of the printing line to bring any line of type to printing position and being movable in the direction of the printing line, an

inking device for coöperating with the lines of type, and mechanism for shifting the inking device out of coöperation with the lines of type when the printing member is moved 5 in the direction of the printing line.

25. In a printing machine, a rotary printing member having a plurality of lines of type thereon extending in the direction of the axis of turning of said member, an 10 inking device for coöperation with the lines of type when the printing member is turned about its axis, and a device carried with the inking device and adapted to engage the printing member between the lines of 15 type to move the inking device out of co-operation with the printing member when

the latter is shifted in the direction of its axis.

26. In a printing machine, a rotary printing member having a plurality of lines 20 of type thereon extending in the direction of the axis of turning of said member, an inking roller, a frame by which said roller is carried, a spring acting on said frame to hold the roller in coöperation with the printing member when the latter turns about its axis, and a device carried by said frame and adapted to engage the printing member when the printing member is moved in the direction of its axis. 25

HENRY J. PLANT.
